ALFRED PEDERSON Inventor

By Richard Oliver.

Attorney

UNITED STATES PATENT OFFICE.

ALFRED PEDERSON, OF COLFAX, WISCONSIN.

LANTERN HEATER.

Application filed June 3, 1925. Serial No. 34,680.

This invention appertains to a novel attachment for lanterns and the like, whereby the lanterns can be used for cooking, as well as for lighting purposes.

5 The primary object of the present invention is the provision of a novel attachment, which is adapted to be readily associated with a lantern of conventional form and which is so constructed as to direct the heat 10 from the upper end of the lantern to a hot plate or the like, on which the receptacle containing the food to be cooked can be placed.

15 A further object of the invention is to provide a novel cooking attachment for a conventional lantern of the above character, which will be durable and efficient in use, one that will be simple and easy to manufacture and one which can be placed upon the 20 market and incorporated with a lantern at a small cost.

With these and other objects in view, the invention consists in the novel construction, arrangement and formation of parts, as will 25 be hereinafter more specifically described, claimed, and illustrated in the accompanying drawings, in which drawings:

Figure 1 is an elevation of the improved attachment associated with the upper end 30 of a conventional lantern,

Figure 2 is a top plan view of the same,

Figure 3 is a diametric section through the attachment taken on the line 3—3 of Figure 2 looking in the direction of the arrows,

Figure 4 is a diametric section through a slightly modified form of the invention showing the hood of the lantern removed, and

40 Figure 5 is a horizontal section taken on the line 5—5 of Figure 4 looking in the direction of the arrows.

Referring to the drawings in detail, wherein similar reference characters designate corresponding parts throughout the several views, the letter A generally indicates the improved attachment and B a lantern with which the same can be associated.

45 The lantern B can be of any preferred type or make, such as the Coleman gasoline lantern, and therefore only a portion of the lantern has been disclosed in the drawing. As shown the lantern B embodies the usual

globe 10 and the cap 11. The cap 11 includes a top plate 12 having the raised central portion 13 carrying the axially disposed chimney or sleeve 14, over which an inverted substantially conical deflector 15 is placed. This deflector permits the escape of heat 55 from the chimney or sleeve 14 and the chimney or sleeve can be provided with a plurality of openings 16. The heat deflector 15 is held in place in any desired way, such as by a stove bolt 17.

The improved attachment A is so constructed as to readily fit on top of the lantern so as to permit the same to be readily used in connection therewith and it is to be noted that the lantern can be simultaneously used for lighting and cooking purposes. 60 The attachment A embodies a sheet metal body 20, which I have shown in Figures 1 to 3 inclusive to be of an inverted frustoconical form and the tapered end of the body 20 is adapted to fit upon the raised portion 13 of the cap so as to snugly receive the perforated sleeve or chimney 14. The upper enlarged end of the body 20 can be provided with an inwardly directed flange 21 on which is adapted to be placed or secured 65 the top wall 22, which forms a hot plate, upon which the cooking utensil can be placed. If preferred the marginal edge of the top plate 20 can be provided with a standing flange 23, so as to prevent the accidental sliding off of the cooking utensils 70 from the top plate. While the attachment can be used with the lantern without any positive holding means, I have shown in Figures 2 and 3 of the drawings the stove bolt 17 passing through the top plate 21.

In Figures 4 and 5 I have shown a slightly modified form of the invention, in which the body is in the nature of a cylindrical drum 25 and the lower edge of the drum is 75 adapted to fit upon the plate 12 and to snugly receive the raised central portion 13. It is to be noted in this form that the drum carries the top wall hot plate 26.

In some instances, it might be advisable 80 to remove each deflector 15 from the lantern and in Figure 4 of the drawings this deflector has been removed. In this instance the drum 25 takes the place thereof.

From the foregoing description, it can be 85 seen that I have provided a novel cooking

attachment for a conventional lantern whereby articles of food can be readily cooked thereon.

Changes in details may be made without departing from the spirit or scope of the invention, but:

What I claim as new is:

1. The combination with an illuminating lantern embodying a globe and a cap comprising a top plate resting on top of the globe and having a centrally raised portion carrying an axially disposed sleeve, of an attachment therefor comprising a drum adapted to snugly fit over a portion of the cap, and a plate resting on top of the drum and

provided with a peripheral upstanding flange adapted to retain on said plate an article to be heated.

2. An attachment for illuminating lanterns comprising a cap embodying a plate adapted to rest on top of the globe of the lantern and being provided with a centrally raised portion carrying an axially disposed sleeve, a drum snugly fitting over a portion of the cap, and a plate resting on top of the drum and provided with an upwardly directed peripheral flange adapted to retain on said plate an article to be heated.

In testimony whereof I affix my signature.

ALFRED PEDERSON.
